UNITED STATES PATENT OFFICE.

CHARLES W. DAKE, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

HEADLIGHT.

1,098,318.

Specification of Letters Patent. Patented May 26, 1914.

Application filed April 25, 1913. Serial No. 763,511.

To all whom it may concern:

Be it known that I, CHARLES W. DAKE, a citizen of the United States, residing at Chicago, in the county of Cook and State of Illinois, have invented a certain new and useful improvement in Headlights, of which the following is a specification.

My invention relates to improvements in headlights and is illustrated diagrammatically in one form in the accompanying drawings, wherein—

Figure 1 is a front elevation; Fig. 2 is a vertical section; Fig. 3 is a horizontal section; Fig. 4 is a detail section of the lamp bracket support; and Fig. 5 is a section along line 5—5 of Fig. 2.

Like parts are indicated by the same letter throughout the several figures.

The integral headlight casing A provided with the flat supporting base A¹ has the flaring front A². A lens sleeve B is hinged at B¹ on the housing A adapted to swing into and engage the flaring front A² and carries a lens or projector B². A parabolic reflector B³ located within the housing A and concentric with the lens B² extends forward as far as the flaring front A². The reflector is slotted at B⁴ as indicated. A lock B⁵ is provided to hold the lens sleeve in position.

The number plates C, C¹ on either side of the housing are pivotally mounted and provided with locks C² to hold them in position. The housing is built out as at C³ to support these number plates and contains the light C⁴ to illuminate them.

A bracket support D is rigidly attached to the base of the housing and is provided with a segmental spherical bearing or surface D¹. A ball D² rests on this bearing or surface and is adapted to be held in position thereon by a plate D³ having a segmental spherical surface D⁴ in opposition to the ball. This plate engages a lug D⁵ projecting from the bracket D on one end and is on the other end held down by the thumb screw D⁶ and clamped against the ball.

A tube E is slidable in the sleeve E¹ projecting upwardly from the ball and may if need be slide clear through the opening E² in the ball. A thumb screw E³ is provided to hold the sleeve against movement and permit adjustment. An electric light socket E⁴ located on the end of the sleeve carries the

light bulb E⁵. A conductor E⁶ leads from the bulb E⁵, through the sleeve E, the ball E², out beneath the bracket D, to the binding posts E⁷ on the back of the housing.

It will be evident that, while I have shown in my drawings an operative device, still many changes might be made in size, shape and arrangement of parts without departing materially from the spirit of my invention. I wish therefore, that my drawings be regarded as in a sense diagrammatic. 65

The use and operation of my invention are as follows: The lens sleeve may be swung out on its hinge to permit access to the electric light bulb or to the interior of the reflector for cleaning purposes. Adjustments of the position of the electric light bulb with respect to the parabolic reflector such as are absolutely necessary in focusing the light from such an electric headlight are permitted by manipulation of the support within the housing beneath the parabolic reflector, access to this being had through the space occupied by the illuminated number plates which may be swung out for that purpose. The bracket upon which the lamp is supported is, of course, fixed, but the lamp tube or shaft is slidable in the ball on the bracket and may be thus moved to the proper vertical position and locked by the thumb screw. Meanwhile, 85 however, when the ball clamp is released the bulb may be moved about in any position desired and finally locked in position when correctly placed. Thus absolutely universal adjustment is provided, and the electric light bulb may be placed in any desired position in the parabolic reflector at the will of the operator and may be easily and conveniently locked there, since the two adjustments are quite sufficient to place it without further difficulty. The conductors, it will be noticed, pass through the sleeve and the ball and are connected with the binding posts at the rear of the housing so that once the light is focused it is necessary only to connect the supply wires to the binding posts on the outside of the housing without interfering with its arrangement, thus giving a readily adjusted and readily applied headlight. 90

It will be noted that the lens sleeve seats upon the flange about the outer periphery of the parabolic reflector and thus gives a tight

closure to said reflector about its periphery and prevents to a large extent the entrance of foreign substances which would be inclined to tarnish the reflector. The single 5 elliptic opening in the reflector through which the sleeve or tube supporting the light bulb enters is not large enough to permit any very appreciable circulation of air into and out of the reflector, and thus it is 10 normally filled with dead air and the introduction of foreign substances is prevented. The opening in the wall of the casing through which the conductors pass is, of course, closed by the conductors and insulating material and thus again the entrance 5 of foreign matter is largely prevented.

I claim:

1. In a lamp support for a locomotive headlight the combination of a hollow 20 standard to which the lamp is attached with a socket comprising a hollow stem in which the hollow standard is slidably received, means to secure the standard in the stem and a hollow ball, a perforated plate on 25 which the ball rests, a locking plate above the ball, means for clamping the stem upon the ball and conductors which lead from the lamp through the hollow standard, stem and ball to the binding posts.
2. In a lamp support for a locomotive headlight the combination of a standard to which the lamp is attached with a socket comprising a hollow stem in which the standard is slidably received, means to secure 35 the standard in the stem and a hollow ball, a perforated plate on which the ball rests, a locking plate above the ball with means for clamping the stem upon the ball and conductors which lead from the lamp

through the stem and ball to the binding 40 posts.

3. In a lamp support for a locomotive headlight the combination of a hollow standard to which the lamp is attached with a socket 45 comprising a hollow stem in which the hollow standard is slidably received, means to secure the standard in the stem and a hollow ball, means for clamping the hollow ball in any desired position and conductors which lead from the lamp through 50 the hollow standard, stem and ball to the binding posts.

4. In a lamp support for a locomotive headlight the combination of a standard to which the lamp is attached with a socket 55 comprising a hollow stem in which the standard is slidably received, means for securing the standard in the stem and a hollow ball, means for clamping the ball in any desired position and conductors which lead 60 from the lamp through the hollow stem and wall to the binding posts.

5. In a lamp support for a locomotive headlight the combination of a standard to which the lamp is attached with a socket 65 comprising a hollow stem in which the standard is slidably received, means to secure the standard in the stem and a ball and means for locking the ball in any desired position and conductors which lead 70 from the lamp to the binding posts.

In testimony whereof, I affix my signature in the presence of two witnesses this 18th day of April 1913.

CHARLES W. DAKE.
